CLAIM

The ornamental design for reversible gown, as shown and described.

DESCRIPTION

FIG. 1 is a perspective view of a reversible gown, with an exterior surface oriented outward, and showing our new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and

FIG. 7 is a bottom plan view thereof.

FIG. 8 is a perspective view of the reversible gown of FIGS. 1-7, with an interior surface oriented outward, and showing our new design;

FIG. 9 is a front elevation view thereof;

FIG. 10 is a rear elevation view thereof;

FIG. 11 is a right elevation view thereof;

FIG. 12 is a left elevation view thereof;

FIG. 13 is a top plan view thereof; and,

FIG. 14 is a bottom plan view thereof.
